UNITED STATES PATENT OFFICE.

F. K. HAIN, OF RENOVO, PENNSYLVANIA.

IMPROVEMENT IN AXLE-BOX COVERS.

Specification forming part of Letters Patent No. **58,640**, dated October 9, 1866

To all whom it may concern:

Be it known that I, F. K. HAIN, of Renovo, in the county of Clinton and State of Pennsylvania, have invented a new and Improved Axle-Box Cover; and I do hereby declare that the following is a full, clear, and exact description thereof, which will enable those skilled in the art to make and use the same, reference being had to the accompanying drawings, forming part of this specification, in which—

Figure 1 represents a perspective view of this invention. Fig. 2 is a front view of the same. Fig. 3 is an end view of the same. Fig. 4 is a plan or top view of the same.

The remaining figures are details which will be referred to as the description progresses.

Similar letters of reference indicate corresponding parts.

This invention relates to an axle-box cover, which is provided with two gudgeons intended to work in suitable eyes on the box. One of these eyes is open on top, so that the cover, when turned clear up, can be removed, and in the other uncut eye a spring is placed, which presses against the end of the gudgeons and forces the cover up against the inner shoulder of the cut or open eye. This shoulder is provided with a notch, into which the cover catches, so that it is prevented from opening spontaneously, and the inner edges or shoulders of both eyes form inclined planes, which, in combination with the spring aforesaid, render the cover self-closing.

A represents an axle-box of any desirable construction and made of cast-iron or any suitable material. This axle-box is furnished with a cover, B, which is provided with two gudgeons, *a b*, projecting from a lug, *c*, that ex-

tends from the top edge of the cover. (See Fig. 1.) These trunnions work in eyes *d e*, cast with or otherwise connected to the box A; and the eye *d* is cut open on top, so that the cover, when turned clear up, can be readily removed.

The eye *e* is left solid all round, and in its interior is introduced a spiral spring, *f*, (see Fig. 10,) which presses against the end of the gudgeon *b*, and if the cover is closed down the edge of the lug *c* is forced into a notch, *g*, in the inner edge of the open eye *d*, whereby said cover is held in position and prevented from opening spontaneously.

The inner edges of both eyes *d e* form inclined planes *h*, and by the combined action of these inclined planes and of the spring *f* the cover is rendered self-closing.

By these means an axle-box cover is obtained which is securely held in its place, and which cannot get lost, because it can only be disengaged from the box if it is turned clear up. Said cover is also so arranged that it has a tendency to close down and stay closed, so that it cannot easily be left open by neglect or fly open from some other cause, and the entrance of dirt and dust is effectually prevented.

What I claim as new, and desire to secure by Letters Patent, is—

The cover B, trunnions *a b*, spring *f*, eyes *d e*, with inner inclined planes, the eye *d* being open and provided with notch *g*, and the box A, combined and arranged substantially as described, for the purpose specified.

F. K. HAIN.
